UNITED STATES PATENT OFFICE.

IDA V. BENOIT, OF BROOKLYN, NEW YORK.

SEPARABLE FASTENER.

1,254,648.

Specification of Letters Patent. Patented Jan. 29, 1918.

Application filed March 20, 1917. Serial No. 156,041.

To all whom it may concern:

Be it known that I, IDA V. BENOIT, a citizen of the United States, residing at Brooklyn, in the county of Kings and State of New York, have invented certain new and useful Improvements in Separable Fasteners, of which the following is a specification.

This invention relates to separable fasteners of the head and socket type, such as are used as a substitute for buttons.

Fasteners of this type have heretofore been proposed, comprising a rigid head and a resilient socket member, but in such prior devices it has been necessary to secure each member to the garment by means of sewing, or the like.

One object of the present invention is to provide a device of this character having means whereby both the head and socket members may be readily attached to and detached from a garment without the necessity for sewing or other securing means. Another object is to so construct such a device that buttons of various ornamental designs may be interchangeably connected to the socket member as desired.

In order that the invention may be readily understood, reference is had to the accompanying drawings, forming part of this specification, and in which,

Figure 1 is a transverse section, showing one of my improved separable fasteners complete as it appears when attached to two portions of a garment to hold the same together;

Fig. 2 is a face view of the socket member;

Fig. 3 is a perspective view thereof, showing the same in its unfinished condition;

Fig. 4 is a rear view of the socket member;

Fig. 5 is a perspective view of the head member, showing the two pieces thereof separated;

Fig. 6 is a transverse section showing a button having means by which it may be attached to the socket member;

Fig. 7 is a transverse section showing a modified construction of socket member; and

Figs. 8 and 9 are perspective views illustrating still further modified constructions of a part of the socket member.

Referring to the drawings in detail, my improved separable fastener comprises socket and head members, designated in

their entirety by the letters A and B, respectively. The socket member A, as clearly shown in Figs. 2 and 3, consists of a disk-shaped shell 1, preferably formed of sheet metal, having an upstanding marginal flange 2, the edges of which are preferably turned over on themselves, as shown in Figs. 1 and 7. Figs. 2 and 3 illustrate the flange before it has been so turned over. In the center of the shell 1 is mounted a dome-shaped socket 3, the shell 1 being cut away underneath this socket to form an opening 4, as shown in Fig. 4. Opposite sides of the base of the socket 3 are cut away, as indicated at 5, to accommodate a spring member 6. This spring member consists of a piece of resilient wire, bent, as shown in Figs. 2 and 3, to form loops 7 and 8, which engage under the flange 2, and one end 9 of which is also formed to engage under such flange. By this means the spring member is held to the shell 1 at three points. Intermediate the fixed points 7, 8, and 9, the spring member comprises a pair of resilient portions 10 and 11, which extend across the sides of the opening 4, as shown in Fig. 4, and serve to grip the head member, as hereinafter described.

The free end of the spring member 10 is brought in under the dome-shaped socket 3 and then bent sharply upward so that it terminates in a pointed post 12, which projects up above the dome 3 and is screw-threaded, as shown in Fig. 3.

The head member consists of two pieces, as shown in Fig. 5. One piece consists of a rigid head 13, secured to a disk or base 14, and provided with a central screw-threaded opening 15. The other piece consists of a disk 16, carrying a central pointed screw-threaded post 17, adapted to enter the opening 15 in the other member. The disk 16 is preferably the same size as the base 14, and may be provided with milled edges, as shown, to facilitate turning.

From the above description, it will be evident that the head member shown in Fig. 5 can be readily attached to a garment at any desired point by simply pushing the post 17 through the cloth and then screwing the member 13-14 down upon the projecting end of the post, thus gripping the cloth between the parts 14 and 16, as clearly shown at y in Fig. 1.

The socket member shown in Figs. 2, 3, and 4, is adapted to be secured in the same manner to another portion *x* of the garment, by means of a coöperating button member. As shown in Fig. 7, this button member comprises a hollow metal body 18, provided at its center on one side with a screw-threaded opening 19, adapted to receive the similarly threaded post 12. When the member 18 is screwed down tight upon this post, it grips the cloth *x* between itself and the socket member or shell 1.

The rigid head 13 is adapted to enter the opening 4 in the socket member, and the resilient portions 10—11 of the spring snap over such head and hold the head and socket members together, in a well known manner.

From the above it will be apparent that my improved head and socket members may be attached to a garment at any desired point and may be readily detached therefrom. It will also be evident that the member 18 may be employed to simulate a button and may be made of any ornamental shape desired.

25 In the case of buttons made of material which does not admit of screw threads being cut therein, as illustrated, for example, at 20, in Fig. 6, a suitable metal socket 21 may be embedded in the button and a screw-threaded opening 19' formed in such socket. In this way, buttons of any desired material may be employed with my improved fastener.

Other ways of forming the post 12 may be adopted. Fig. 7 shows one simple and practical method of forming this post, which consists in striking up a portion 22 from the body of the dome-shaped member 3'. If desired, the post may be separately formed and secured to the socket member as by means of soldering or welding.

40 Figs. 8 and 9 illustrate still other ways in which the post may be formed integral with the gripping means of the socket member.

45 In Fig. 8 the body of the socket member consists of a shell 23, preferably having a peripheral flange, and provided with a central opening 24, adapted to receive the head member. A piece of resilient wire is soldered to the shell 23 as at 25, and is provided with a loop 26, in approximately the form of a circle disposed concentric with the opening 24. The free end of the wire adjacent this loop is bent up at right angles 50 and pointed and screw-threaded to form the post 27, as clearly shown.

In Fig. 9, the shell 28 is of slightly different form, having a flange 29 adapted to be bent over the resilient member. This resilient member comprises a portion 30, which underlies the rim 29 throughout almost the entire circumference of the shell. The ends of the portion 30 are bent inwardly to form a pair of parallel free 60 resilient arms 31 and 32, extending across the

sides of the opening 24, and arranged to grip the head 13 in the same manner as illustrated in Figs. 1, 2, and 3. The arm 32 is bent sharply upon itself at 33, and is again bent outwardly at right angles and 70 pointed and threaded to form a post 34.

Other specific methods of forming and bending the resilient member will suggest themselves to those skilled in the art, but the above examples will serve to illustrate 75 practical ways in which the screw-threaded post can be formed integral with such resilient member, thereby effecting economy in the cost of manufacture.

It will be seen that my improved fastening consists of two members, each of which comprises two parts or elements, and that by clamping the cloth between such parts, as described, the necessity for sewing or riveting is obviated.

80 What I claim is:

1. A separable fastener comprising a socket member and a head member, said socket member being provided with resilient gripping means, and having a central threaded 90 post adapted to engage a button.

2. A separable fastener comprising a socket member and a head member, said socket member being provided with resilient gripping means, and having a screw-threaded 95 post adapted to engage a button.

3. A separable fastener comprising a socket member and a head member, said socket member having a pointed post adapted to pierce the material of a garment or the like, 100 and a button detachably connected to said post so as to grip the material between its self and the socket member.

4. In a separable fastener, a socket member comprising an outer and an inner portion 105 adapted to be placed on opposite sides of the material, a threaded material piercing projection on one of said portions and a threaded aperture on the other portion for detachably engaging said projection.

5. In a separable fastener, a socket member comprising outer and inner portions, one of said portions having an opening 110 therein adapted to receive a stud, a wire secured in said portion to overlie said opening and form a resilient socket for said stud, said wire also having an outwardly projecting portion adapted to secure said portion to the other portion.

6. In a separable fastener, a socket member comprising an outer and an inner portion adapted to be placed on opposite sides of the material, a resilient member coiled within one of said portions and forming a yielding jaw to engage a stud, one portion 115 of said member being formed into a material piercing projection adapted to secure said portion to the material and other portion.

7. In a separable fastener, a socket mem- 130

ber comprising outer and inner portions, one of said portions having an opening therein adapted to receive a stud, a wire secured in said portion to overlie said opening and form a resilient socket for said stud, said wire also having an outwardly projecting threaded portion adapted to detachably secure said portion to the other portion.

8. In a separable fastener, a socket member comprising an outer and an inner portion adapted to be placed on opposite sides of the material, a resilient member coiled within one of said portions and forming a yielding jaw to engage a stud, one portion 15 of said member being formed into a material piercing threaded projection, said other

portion having a threaded aperture adapted to receive said projection.

9. In a separable fastener, the combination with a stud, of a resilient socket member therefor comprising a plate having an aperture therein adapted to receive the stud, a wire secured to said plate having a portion overlying said aperture to form a resilient jaw, said wire also having a rearwardly extending portion adapted to secure 20 said socket member to the material to be fastened.

In testimony whereof I have affixed my signature.

IDA V. BENOIT.
